UNITED STATES PATENT OFFICE.

PETER DARMSTADT, WILHELM STEGMANN, AND VALENTIN WEIL, OF FECHENHEIM, NEAR FRANKFORT-ON-THE-MAIN, GERMANY, ASSIGNORS TO THE FIRM DRAHTINDUSTRIE PETER DARMSTADT & CO. G. M. B. H., OF FRANKFORT-ON-THE-MAIN, GERMANY.

MULTIPLE-WIRE-DRAWING MACHINE FOR DRAWING FINE WIRES FROM SUITABLE MATERIAL.

Application filed January 11, 1928, Serial No. 245 834, and in Germany February 28, 1927.

The subject of the present invention is a multiple wire drawing machine for drawing fine wires from suitable material, in which the size of the angle of bending, with which the wire bears firmly on the drawing rolls or drawing rollers arranged between each pair of drawing stones or dies, is less than 180°; in comparison with the usual drawing machines, in which this angle of bending is 10 180° or more. The machine known hitherto, particularly when using a high speed of rotation of the drawing members, operate uneconomically by reason of the frequent breakage of the thin wires caused by the too 15 large angle of bending. In order to remedy this defect it has already been suggested to subdivide a large angle of bending of more than 180° into a plurality of small angles of bending—the sum of the angles of bending 20 however always amounting to more than 180°—but the breakage of the thin wires still occurs too frequently. As drawing rolls or drawing rollers in the sense of the invention there are only to be understood those 25 rolls or rollers against which the thin wire to be drawn bears firmly and which impart work to the drawing system by mechanical drive, and therefore must overcome the drawing resistance of the wire in the drawing 30 stones or dies. In addition to the purely drawing strain the wire also always receives an additional strain on the drawing rolls or drawing rollers which increases with the size of the angle of bending with which it 35 bears firmly on these, according to the known formula for belt drives, and when a predetermined limit is exceeded must lead to the breakage of the wires.

For the production of fine wires, angles of 40 bending of the magnitude of 180° and more as previously used, whether subdivided or not, are therefore unsuitable as the total strain to which the thin wire may be subjected may reach an amplitude which exceeds 45 the tensile strength still existing at the points subjected to strain so that it must break.

According to the present invention this 50 disadvantage is overcome in that the angle of bending by means of which the wires firmly bear against drawing rolls or drawing rollers located between each two drawing stones or dies, is in all cases made smaller

than 180°. Practical results have shown that an angle of bending considerably below 180° suffices for drawing, for example, without trouble nickel wires of 0.1 mm. diameter. 55

The drawing rolls or drawing rollers may be arranged in any suitable manner, according to the construction of the machine which is used. They may be arranged behind one another, side by side or one over the other, or also behind one another and side by side or one above the other. In addition to the actual drawing rolls or drawing rollers guiding or reversing rolls or rollers may also be 60 provided around which the wire passes loosely and which serve to reverse the direction of pull of the wire or to guide the wire in a continuous or circular path. These guiding or reversing rolls do not impart any work to the 65 drawing system, and therefore do not require a mechanical drive. In connection with these the angle of bending may be of any suitable size as the wire is not subjected to an additional strain and the breakage of 70 the thin wire, for the reasons set out above 75 is not to be feared.

The angle of bending of the wire around the several drawing rolls or drawing rollers can be made progressively smaller according 80 to its gradual reduction in cross section and strength. The adjustment of the angle of bending necessary at any time can for this purpose be effected by relatively adjusting the drawing members, or in machines having separate guiding systems, by adjusting the drawing members and/or the guiding 85 members relatively to one another. All the operative parts, for the purpose of adjusting the machine for different drawing ranges or 90 for producing wires of different diameters, are preferably arranged so as to be exchangeable.

On the periphery of the drawing rolls or drawing rollers we prefer to provide either 95 fixed rings or loose rings driven by friction over which the wire is guided and which can be conveniently replaced or exchanged after wear. Loose rings driven by friction also serve for equalizing any stoppages which may 100 occur in the uninterrupted drawing of the wires and which may be caused by failure of the various drawing rolls or drawing rollers to deliver or take up the wire quite uni-

formly. According to the tightening or yielding of the wire and the increase, reduction or ceasing of friction due thereto between the rings and the peripheral surface 5 of the drawing rolls or drawing rollers, equalization of the difference in speed between each pair of drawing stones or dies will be obtained during the progress of the drawing operation.

The invention is illustrated in different 10 examples of application and construction in the accompanying drawings, wherein:

Figure 1 is an elevation of a multiple wire drawing machine in which the wire is drawn in a continuous operation through the bores 15 of a number of drawing dies arranged one behind the other, which bores become smaller from the unwinding coil to the winding coil the wire being fed by means of drawing rollers mounted between each pair of drawing 20 dies and driven in any suitable manner.

Figure 1^a is an end elevation of the cam drive for the wire guide on the winding spool.

Figure 2 shows diagrammatically the arrangement of the drawing rolls in such a machine having drawing rolls of the same diameter which rotate at different speeds and in which the angle of bending is smaller towards the side of the winding roll.

Figure 3 shows diagrammatically a construction in which the drawing rolls have a diameter which is increased towards the winding spool and rotate at the same speed.

Figure 4 shows a diagrammatic illustration of a form of construction with two drawing rolls between each pair of drawing dies.

Figure 5 shows a diagrammatic illustration of a form of construction with two rows of drawing rolls arranged one above the other and a reversing guide roll for returning the 40 wire, so as to dispose a long drawing distance within a short space.

Figure 6 is a diagrammatic end elevation of a form of construction with drawing dies arranged side by side, a number of drawing 45 rollers running in the same direction and a guide roller for returning the wire in a circle towards the next succeeding drawing dies.

Figure 7 shows a diagrammatic perspective end elevation of a drawing roller and 50 two guide rollers, and

Figure 8 is a diagrammatic end elevation of the same form of construction, which in combination with that illustrated in Figure 7 shows how, by adjusting a guide roller, the 55 angle of bending at said roller may be altered.

In all the figures *a* indicates the drawing dies, *b* the drawing rolls or drawing rollers, *c* the guide rolls or rollers, *d* the wire to be drawn, *e* the unwinding spool and *f* the winding spool. The angle of bending at the drawing 60 rolls or drawing rollers is shown shaded in thin lines for the sake of greater clearness.

For the same reason the guide rolls or rollers are shaded with crossing lines.

65 In Figure 1 *g* indicates the bearing blocks

for the drawing rolls or rollers *b* and *h* those for the drawing dies *a*. These blocks are formed as slides and are relatively movable and adjustable on the base plate *i* of the machine. The drawing dies *a* are mounted on 70 the supporting blocks *h* preferably in universal ball joints so that an accurate directing adjustment of the die bores relatively to the drawing direction of the wire can be effected. *k* is a tension roller for the wire to 75 be drawn from the spool *e* and *l* the guide roller for the wire passing on to the spool *f* and uniformly wound thereon. The support *m* for the guide roller *l* is uniformly reciprocated in accordance with the amount of spool 80 length in slide guides by means of suitable gearing *n* with a cam member *o* and lever transmission mechanism *p* (see also Figure 1^a). The drawing rolls or rollers are driven by means of crossed belts from the main shaft 85 *r* in the same direction at a rotary speed which increases towards the winding spool *f*. The adjustment of the drawing rolls or rollers *b* is effected in this construction only in a horizontal direction.

In the forms of construction according to Figures 2 and 3 the drawing rolls or rollers *b* are movable and adjustable both in a horizontal and in a vertical direction and are so adjusted that the angles of bending become 90 smaller from the unwinding spool to the winding spool in accordance with the reduction of cross section of the wire. According to Figure 2 the drawing rolls or rollers *b* all have the same diameter and according to 100 Figure 3 their diameters increase progressively towards the winding spool. In order to compensate for the increase in length of the wire towards the winding spool *f* during the drawing operation, the drawing rolls or rollers, according to the arrangement in Figure 2 must rotate at an increasing speed, whereas according to the arrangement in Figure 3 they may be driven at a constant speed of rotation.

According to Figure 4 where the drawing dies and drawing rolls or rollers are arranged one behind the other, the drawing operation is facilitated by arranging two drawing rolls between two successive dies. The drawing 110 rolls or rollers as arranged in Figure 5 correspond with the arrangement according to Figure 1. The distance of drawing is however doubled by superimposing two rows of drawing rolls or rollers, and a separate guide or return roll or roller *c* is provided over which the wire *d* is guided loosely back to the lower row of drawing members. The guide roll or roller *c* rotates loosely. It could however also be driven but in this case would 120 have to be driven at such a speed that it does not exert any pulling action on the wire.

In the forms of construction according to Figures 6, 7 and 8 the drawing dies *a* are arranged side by side and separate guiding 130

rolls or rollers *c* are provided over which the wire to be drawn is guided and from the other side of which it is then drawn through the bore of the laterally disposed succeeding drawing dies.

According to Figure 6 only one guide roll or roller *c* is provided and opposite this are four drawing rolls or rollers *b* which all rotate in the same direction. The drawing dies 10 *a* are arranged between the guide roll *c* and the first of the four drawing rolls *b*, a suitable number of which are provided, for the purpose of facilitating the drawing operation as in the construction according to Figure 15 4.

According to Figures 7 and 8 there are provided in addition to a single drawing roll or roller *b*, two guide rolls or rollers *c* and these are so arranged in relation to the drawing roll 20 or roller that by a relative variation of the position of all the rolls or rollers the angle of bending on the drawing roll or roller *b* can be varied.

Figure 8 in conjunction with Figure 7 is 25 adapted to show how by lateral movement of the lower guide roll *c* the angle of bending on the drawing roll is enlarged relatively to that in the arrangement according to Figure 7. Instead of relatively moving all the rolls 30 or rollers either only the drawing roll can be movably mounted in relation to the guide rolls, or the latter or one thereof relatively to the drawing roll. For purposes of illustration (see Fig. 7) a bearing block *g*, similar to those provided in Figure 1, is shown 35 for carrying and adjusting the position of the upper guide roll *c*. The shaft *s* of the driving roll and the shaft *s'* of the lower guide roll may be mounted in the same fashion as 40 the upper guide roll.

Having now described our invention, we 45 wish it to be understood that various changes in the arrangement and combination of parts may be made, which changes are to be limited only by the scope of the appended claims.

We claim:

1. In a multiple wire drawing machine for drawing fine wires, the combination, with a plurality of dies, of a drawing roll between 50 each pair of said dies, the arrangement being such that the wire to be drawn bears against each of said drawing rolls at an angle of less than 180°, the angle of bending on each drawing roll being smaller than the angle of bending around the previous drawing roll according to the reduction in cross-section of the wire.

2. In a multiple wire drawing machine, a

plurality of pairs of drawing dies, a single drawing roll between each pair of dies, the drawing rolls being alternately disposed above and below successive pairs of dies and arranged for only partial peripheral contact with the wire, the wire thus passing from a die over one roll to a second die and thence 60 from said second die under a roll to a third die, and means for adjusting the said rolls and die relatively to each other for changing the angles of bending of the wire between the dies. 65

3. In a multiple wire drawing machine, in combination with a set of drawing dies, drawing rolls mounted between said dies and arranged for only partial peripheral contact with the wire, separate guide rolls for guiding the wire through large distances of drawing, means for adjusting the drawing rolls and the guide rolls relatively to each other to vary the angle of partial peripheral contact of the wire with the drawing rolls, and 70 universal ball joints, the dies being mounted in said joints in order for their bores to automatically align themselves with the directions of travel of the wire as said directions vary with changes in the angles of partial peripheral contact. 75

4. In a machine as defined in claim 2, universal ball joints, the dies being mounted in said joints in order for their bores to automatically align themselves with the direction of travel of the wire as said direction varies with the angle of bending. 80

5. In a wire drawing machine, two dies through which the wire is adapted to pass successively, and a drawing roll arranged to 85 engage the wire on its way from the first of said dies to the second, along a peripheral contact portion of less than 180°, the wire passing directly from the first die to the drawing roll and directly from the drawing roll to the 90 second die. 100

6. A multiple wire drawing machine comprising a plurality of dies through which the wire is adapted to pass successively, and a drawing roll mechanism arranged to engage 105 the wire on its way from each of said dies to the next, along a peripheral contact portion the angular extent of which decreases progressively between successive pairs of dies, as the cross-section of the wire is reduced. 110

In witness whereof we have hereunto set our hands.

PETER DARMSTADT.
WILHELM STEGMANN.
VALENTIN WEIL.
